(57) **CLAIM**

We claim the ornamental design for a coffee cup lid.

DESCRIPTION

FIG. 1—is a perspective view of a coffee cup lid;
FIG. 2—is a perspective view of the underside of the coffee cup lid;

FIG. 3—is a first side view of the coffee cup lid;

FIG. 4—is a back view of the coffee cup lid;

FIG. 5—is a front view of the coffee cup lid;

FIG. 6—is a second side view of the coffee cup lid;

FIG. 7—is a top view of the coffee cup lid; and,

FIG. 8—is an overhead view of the underside of the coffee cup lid.

In the drawings, the broken lines showing portions of a coffee cup lid depict environment and form no part of the claim.
